UNITED STATES PATENT OFFICE.

JOHN D. HILLIARD, OF SCHENECTADY, NEW YORK, ASSIGNOR TO GENERAL ELECTRIC COMPANY, A CORPORATION OF NEW YORK.

ELECTRIC SWITCH.

Application filed February 8, 1921. Serial No. 443,440.

To all whom it may concern:

Be it known that I, JOHN D. HILLIARD, a citizen of the United States, residing at Schenectady, in the county of Schenectady, 5 State of New York, have invented certain new and useful Improvements in Electric Switches, of which the following is a specification.

This invention relates to electric switches 10 and particularly to switches of that type in which the circuit is interrupted in an insulating liquid.

When opening high power circuits under oil the arc formed upon the separation of 15 the switch electrodes causes a certain amount of oil to be dissociated or volatilized, thus producing a large quantity of highly heated gas. The pressure produced may be sufficient to throw oil out of the oil tank and 20 even to burst the tank itself. The oil is thrown out of the oil tank in a more or less atomized condition and as it is often carbonized, forms a black deposit upon the surrounding objects. Following the oil is the 25 highly heated gas which upon contact with the air may ignite and cause a secondary explosion of more or less violence. The heated gas often ignites within the oil tank upon contact with the air above the surface 30 of the oil, thereby causing explosions violent enough to burst the oil tank or tear it loose from its foundation. Even where the direct injury from the explosion is slight, the fire risk in the station is increased, and instances have occurred where the explosion 35 has resulted in a short circuit which has seriously interfered with the delivery of power to consumers.

Numerous attempts have been made in 40 the past to render the opening of high powered circuits possible without danger. Baffles and screens have been arranged in different ways within the oil tank to impede the movement of the oil and gas, or to separate the oil from the gas and allow only the latter to escape, or to prevent any flare-back 45 of the burning gases to the interior of the oil tank, and tubes have been employed as vents within which the escaping products may be 50 cooled before coming into contact with the air. Although many of these devices have improved the operation of oil switches, none of them, so far as applicant is aware, have made possible the opening of the very high 55 powered circuits at present in use with the

degree of safety demanded in modern practice.

According to my present invention I so construct the switch that when the circuit is broken under oil practically no oil is ejected from the oil tank and secondary explosions caused by contact of heated gas with the air are prevented. To this end I interpose in the path of the fluids set in motion by the arc a means which will prevent the ejection of liquid from the tank, separate a large portion of the oil vapor and atomized oil from the gas and also cool the fluids ejected from the tank to a temperature below that at which the fluids spontaneously ignite upon contact with the air, or to a temperature such that they are no longer dangerous to the installation. These various effects are accomplished by causing the moving fluid to be broken up into a plurality of fine streams which are caused to flow through circuitous passages through cooling material. I preferably arrange these passages in or to communicate with the upper part of the oil tank. The pressure created by the arc 60 throws a certain quantity of liquid oil toward the top of the tank and into these passages, where its flow is impeded, so that the gases generated at the arc have an opportunity to rise within the tank and enter the passages before any great quantity of liquid has entered them, and thereby the separation of the oil and gas is facilitated. I find that by making the path taken by the streams of fluid circuitous rather than 65 straight I am able to effect the desired condensation and reduction of temperature of the fluids with a comparatively small volume 70 of cooling material.

While the specific embodiment of the 75 means above described may take a variety of forms, I prefer to employ for this purpose a perforated baffle or barrier composed essentially of a mass of pebbles or small fragments, for example, gravel or similar material, so arranged that the projected fluids are forced through the gravel.

This application is a continuation in part 80 of my application, Serial No. 332,621, filed October 23, 1919, electrical apparatus, and 85 assigned to the assignee of the present application. In my prior application, I have disclosed the use of a gravel baffle in connection with fluid break electric switches.

The modified forms of my invention 90

shown by Figs. 4, 5 and 6 are described and claimed specifically in my copending applications Ser. No. 602,703, electric switches, filed November 23, 1922; Ser. No. 602,702, 5 electric switches, filed November 23, 1922; and Ser. No. 491,128, electric switches, filed Aug. 10, 1921 respectively, which are also assigned to the same assignee as the present application.

10 Other objects and advantages will appear as the description proceeds.

Referring to the accompanying drawings, Fig. 1 shows in elevation and partly in section a switch provided with a movable perforated baffle constructed in accordance with my invention; Fig. 2 is a similar view of a modified form of switch in which the perforated baffle is stationary; Fig. 3 is a detail showing a slightly different means for holding gravel in the baffle; Figs. 4 to 6 inclusive are sectional views showing the application of my invention to other forms of switches.

Referring to Fig. 1, 10 represents a tank or casing which is provided with a cover 11. This tank and casing should be constructed to withstand considerable internal pressure. Supported from insulators 12 which are carried by the cover are stationary contacts 13 of the switch. The movable contacts 14 are carried upon a rod 15 which extends upwardly through an opening 16 formed in the cover 11. Cover 11 may be spaced from the top of the tank 10 at points around its periphery as indicated at 17 to form vents. Located within the tank 10 is a baffle which comprises a top portion 18 and a depending portion 19 which in the switch shown is preferably of cylindrical form. The top portion 18 is formed of a casing 20 composed of horn fibre or similar material and has perforated top and bottom plates 22 between which is located the granular material 23. This material is preferably one which has a high dielectric strength, such for example as quartz gravel. The gravel may vary considerably in size but for many switches I find that pebbles from $\frac{1}{2}$ to $\frac{3}{4}$ inch in diameter are very satisfactory. 40 However, it should be noted that while I refer to this material as gravel, I desire it to be understood that I do not wish to limit myself to any particular size of pebbles or particles of which this material is composed.

50 Suitable openings 24 and 25 are provided for the passage of two insulators 12 and the rod 15 through the body portion of the baffle thereby allowing the baffle to move vertically within the container, and suitable blocks 9 are provided against which the baffle may bear in its upper portion. Fig. 1 shows the baffle raised somewhat from its lowermost position in which latter position the depending portion 19 will rest upon the bottom of the tank 10. In practice the tank

10 is filled with oil to the level indicated which in the lower position of the baffle completely fills the space beneath the top portion 18. In operation, upon the opening of the switch, the arc produced generates gas or vapor depending in quantity upon the intensity and duration of the arc. The depending portion 19 prevents the gas from escaping around the baffle and the pressure produced by the generation and 75 expansion of these gases raises the baffle which thus acts as a safety device to prevent the pressure from becoming excessive. The limitation of pressure is desired not only because of the fact that too great a 80 pressure will cause direct injury to the apparatus, but also because the amount of gas generated by the arc is dependent upon the pressure upon the arc stream. The gas upon being liberated rises in the oil and passes 85 up through the body portion of the baffle where it is cooled by contact with the gravel and a portion of the same condensed. The remainder has its temperature so lowered 90 that it will not ignite when it comes in contact with the air.

In the form shown in Fig. 2 the baffle is stationary and comprises a casing 28 suitably secured to the cover 11. The casing may be perforated along its bottom and 95 sides and spaced at its sides from the wall of the tank 10.

In Fig. 3 I have shown a modified form of baffle in which a wire netting 30 may be placed between the gravel and the containing casing 31. This would have the advantage of strengthening the baffle. If desired, the baffle may be formed of a quantity of such woven or unwoven wire folded, bent or otherwise compressed into the space within the casing 31.

In Fig. 4 is illustrated the application of my gravel baffle to a switch of the so-called explosive or oil blast chamber type. That portion of the apparatus illustrated in Fig. 4 is adapted to be immersed in an oil tank, not shown, and the electrode 33 is adapted to be secured to an insulator which passes through the cover of the tank. Rigidly secured to the electrode 33 is a pot 34 formed of a body portion of steel and the bottom likewise of steel. The body portion is formed with valve openings within which are adapted to be seated valve heads 35. The valve heads are carried upon stems 36 which operate in openings 37 formed in a circular plate 38. Springs 39 interposed between the heads 35 and plate 38 serve to force the valves into their seats. Plate 38 is provided with screw threads around its periphery which engage threads 40 formed in a metallic ring 41 set in the insulating shell 42. The plate 38 forms a tight joint between the pot 34 and the shell 42 except for a small bleed hole 43. Between the pot 34 120

and shell 42 is the gravel 44 which is held between perforated rings 45 and 46 of insulated material. These rings are held in place by pins 47 and 48 which extend inwardly from the shell 42. 49 designates an insulator seated in a center opening 50 in the bottom of the pot 34. Through this insulator passes the tubular movable electrode 52. The pot 34 is lined on the inside 10 and covered on the outside with insulated material as indicated at 53.

Normally the oil in and around the shell 42 is maintained above the metal on the lower end of insulator supporting the explosion chamber, the pot 34 being kept full. When the electrodes 33 and 52 are separated to break the circuit, the arc formed creates a pressure which causes oil contained in the pot 34 to be forced downwardly through 20 the center of the electrode 52 and between the electrode 52 and the insulator 49. In operation the upper end of the electrode 52 passes down through the insulator and the blast of oil across the end of the metal tube 25 extinguishes the arc. The pressure within the pot 34 is limited by the valves which open and permit the gas and vapor to escape into the space beneath the plate 38. This space may contain a small amount of air, 30 sufficient to form a cushion for the escaping gas, and so prevent damages to the apparatus by the force of the expulsion. The pressure created in this space causes the oil and gas to be forced downwardly through the gravel 44, after which they rise through the oil in the outer tank and pass through passages similar to those shown in Figs. 1 and 2. It will thus be seen that the device illustrated in Fig. 4 has the advantage of employing an oil blast to extinguish the arc and causes the gas to flow under pressure through a circuitous path to its outlet along a considerable portion of which it passes over the cooling surface of the gravel.

45 In Fig. 5 I have illustrated still another modification in which I combine a double oil blast feature with my improved cooling means. In this form I provide a metallic casing 60 closed at the top by means of a cover 61 having a small outlet passage 62. This casing forms one terminal of the switch and is provided with a stationary contact 63 adapted to cooperate with a movable contact 64. Suspended from the cover 61 by 50 means of the insulator 65 and metal tube 66 is a metallic pot 67. Electrode 64 passes centrally through this pot and between the electrode and the bottom of the pot is located an insulator 68. A small opening 69 serves as a bleed hole for the pot. Extending the length of the casing are wooden rods 70 which are formed with shoulders 71 upon which is supported a perforated ring 72 of insulated material. Between this ring and 60 the perforated ring 73 is the gravel 74.

Baffles 75 and 76 are located above the gravel baffle and these are provided with non-aligned cut-away portions for the passage of gas to the outlet opening 62. Surrounding the movable electrode adjacent its lower end and spaced therefrom is a baffle or partition 77. Baffles 75, 76 and 77 may be supported by tubes of insulation 80 which surround the rods 70.

The operation of this form of invention 75 is as follows: Upon separation of the contacts an arc is formed within the casing 60 beneath the baffle 77. This creates a pressure within the space below the baffle and as the lower end of the electrode 64 passes up through the opening in the baffle a blast of oil is directed into the path of the arc. Likewise, as the end of the electrode 64 moves 80 through the insulator 68 and draws the arc upwardly within the chamber formed by the pot 67 a pressure will be created in this chamber as a result of which oil will be forced from the chamber downwardly through the opening in the insulator 68. It will thus be seen that the two oil blasts moving in opposite directions are projected into the path of the arc and serve effectively 85 to extinguish the same. Gases and vapor which are formed beneath the insulator, as well as any which may pass downwardly 90 through the opening in the insulator, rise through the casing and pass through the gravel 74. Baffles 75 and 76 in addition to furnishing a further cooling surface for the gases serve to lengthen the path to the outlet openings 62. The space beneath the baffle 77 as well as the space within the pot 67 I term a pressure chamber while the space 95 around the pot 67 but within the casing 60 I term a discharge chamber.

100 Fig. 6 shows another form of device in which I take advantage of the pressure of the gas formed by the discharge prior to its cooling to create an oil blast to extinguish the arc. In this form the movable electrode 105 83 passes up through a funnel-shaped opening 87 formed in an insulating partition 84. Surrounding the electrode and depending from the partition 84 is a cylindrical shield 85 of insulating material and connecting the space outside of said shield with the funnel-shaped opening 87 are passages 88 and 89. Baffles 90 and 91 are located above the partition 84 while between the perforated ring 92 and the top 93 of the external casing is located the gravel 94. The tube 95 which passes through the cover 93 and serves to conduct the gas away from the casing 96 also contains gravel. If desired this tube may be extended so that the gas will be discharged at 110 some place remote from the switch. In order to prevent gas in the casing from escaping around the movable electrode, I arrange in the passage 97 through which the electrode 83 operates, a stuffing box 98. This comprises 115 120 125 130

a leather disc 99 which surrounds the electrode 83 and a metal cap 100 against which the disc is forced by the pressure of the gas within the casing. A shield 101 separates 5 the stuffing box 98 from the gravel 94.

In this form, as the electrode 83 is raised to break the circuit, the gases formed cause oil to be projected through the passages 88 and 89 into the path of the arc stream and 10 acts to cool it. The shield 85 serves to keep these jets of oil substantially free from gas.

What I claim as new and desire to secure by Letters Patent of the United States, is:—

1. An oil switch provided with an outlet 15 for the gases formed by the opening of the circuit and a porous mass forming a plurality of extended narrow passages for the escape of said gases located in said outlet.

2. A switch having contacts adapted to be 20 separated beneath the surface of an insulating fluid and a plurality of extended narrow courses of escape through insulated material for the fluid ejected from the space surrounding said contacts upon the opening 25 of said switch.

3. An oil switch provided with an outlet 30 for the gases formed by the opening of the circuit and a cooling means in the path of said gases, said cooling means comprising an aggregation of individual particles with rounded edges.

4. An oil switch provided with an outlet 35 for the gases formed by the opening of the circuit and a cooling means in the path of said gases, said cooling means comprising an aggregation of individual particles with rounded edges, said particles having a diameter of not less than $\frac{1}{8}$ inch.

5. An oil switch having a plurality of extended narrow courses of escape through 40 insulated material for the gases formed by the opening of said switch, said courses being located above the surface of the oil.

6. An oil switch provided with a gravel 45 baffle arranged in the path of the material ejected on the opening of the switch.

7. An oil switch provided with a yielding gravel baffle arranged in the path of the

gases, produced by the opening of the switch. 50

8. In an oil switch, a tank adapted to contain oil, cooperating contacts adapted to be separated beneath the surface of said oil, a movable perforated baffle in the path of the gases produced by the opening of the 55 circuit, the parts being so constructed and arranged as to provide an air space behind said baffle to permit said baffle to yield under the pressure of said gases.

9. A combination of a tank having an 60 outlet at the top thereof, switch contacts within said tank, a vertically movable baffle within said tank, said baffle comprising a body portion formed of a perforated casing and granular material within said casing 65 and an imperforate depending portion which surrounds said contacts and normally rests upon the bottom of said tank, the parts being so constructed and arranged as to provide an air space between the top of 70 said baffle and said outlet.

10. In a fluid switch, the combination of a fluid break containing vessel and cover, insulating fluid within said vessel, separable electrical contacts beneath the surface of 75 said insulating fluid and a perforated barrier supporting granular cooling means in the space above said insulating fluid.

11. In a fluid switch, the combination of a fluid break containing vessel and cover, 80 insulating fluid within said vessel, separable electrical contacts beneath the surface of said insulating fluid and a perforated insulating barrier supporting a non-conducting granular cooling means in the air space 85 above said insulating fluid.

12. In a fluid switch, the combination of a fluid break containing vessel and cover, insulating fluid within said vessel, separable electrical contacts beneath the surface of 90 said fluid, and a movable mass of cooling material in the space above the surface of said insulating fluid.

In witness whereof, I have hereunto set my hand this 7th day of February, 1921.

JOHN D. HILLIARD.

Certificate of Correction.

It is hereby certified that in Letters Patent No. 1,537,353, granted May 12, 1925, upon the application of John D. Hilliard, of Schenectady, New York, for an improvement in "Electric Switches," errors appear in the printed specification requiring correction as follows: Page 4, lines 73, 80, and 88, claims 10, 11, and 12, strike out the word "break" and insert the same after the word "fluid" in lines 72, 79, and 87, of the same claims; and that the said Letters Patent should be read with these corrections therein that the same may conform to the record of the case in the Patent Office.

Signed and sealed this 30th day of June, A. D. 1925.

[SEAL.]

KARL FENNING,
Acting Commissioner of Patents.
